UNITED STATES PATENT OFFICE.

GEORGE A. MEAD AND CHARLES R. STURDEVANT, OF MANSFIELD, OHIO, ASSIGNEES TO THE
OHIO BRASS COMPANY, OF MANSFIELD, OHIO, A CORPORATION OF NEW JERSEY.

RAIL-BOND.

No. 890,367.

Specification of Letters Patent.

Patented June 9, 1908.

Application filed November 25, 1904. Serial No. 234,114.

To all whom it may concern:

Be it known that we, GEORGE A. MEAD and CHARLES R. STURDEVANT, citizens of the United States, residing at Mansfield, in the county of Richland and State of Ohio, have invented a new and useful Rail-Bond, of which the following is a specification.

This invention relates to rail bonds.

The object of the invention is to provide a construction of rail bond wherein provision is made of means for efficiently securing the bond to the surface of a rail or other part to be bonded.

A further object of the invention is to provide the bond terminal with means for retaining solder employed for securing such terminal to the rail surface.

Other objects of the invention will appear more fully hereinafter.

The invention consists substantially in the construction, combination, location and arrangement of parts, all as will be more fully hereinafter set forth, as shown in the accompanying drawing, and finally pointed out in the appended claims.

Referring to the accompanying drawing, and to the various views and reference signs appearing thereon,—Figure 1 is a view in transverse section of a rail or other part to be bonded, showing the application thereto of a rail bond embodying the principles of our invention. Fig. 2 is a view in side elevation of a rail bond terminal showing a form of embodiment of the principles of our invention, the body of the bond being broken off. Fig. 3 is a view in transverse section on the line 3, 3, of Fig. 2, looking in the direction of the arrows. Fig. 4 is a view similar to Fig. 2, showing a modified form of rail bond terminal embraced within the spirit and scope of our invention. Fig. 5 is a transverse section of the same on the line 5, 5, of Fig. 4, looking in the direction of the arrows. Figs. 6 & 7 are broken views in perspective, respectively, of the form of rail bond terminals shown in Figs. 4 and 2.

The same part is designated by the same reference sign wherever it occurs throughout the several views.

In the drawing, reference sign A designates a rail or other part to be bonded, B the fish-plates, and C the bolt by which the fish-plates are clamped together upon the rail. These parts may be of the usual or any ordinary or well known construction and arrange-

ment, and form no part of our present invention.

E designates the rail bond, the body of which may be of any suitable or convenient form or construction.

In the application of rail bonds to rails or other parts to be bonded, it is a common practice to apply the terminals of the bond to the surface of the rail or other part to be bonded, and to secure such terminal to the surface of the rail by solder. In the use of solder for this purpose, it is desirable to provide a pocket or recess, in which the solder is received, to the end that the solder may not be wasted, and may be efficiently employed to secure the bond to the surface of the rail or other part to be bonded.

It is among the special purposes of our present invention to provide a construction of bond terminal wherein a pocket is provided for accomplishing the result stated. A pocket or recess may be formed in many specifically different ways. For instance, and as shown in Figs. 2, 3 and 7, we propose to form a raised rib or projection F on the surface of the bond terminal G which is to be applied to the surface of the rail or other part to be bonded; said raised rib or projection extending along or adjacent to the lower edge and the ends of the terminal portion G of the bond, and hence forming a pocket or recess between the surface of the bond terminal and the surface of the rail, to receive the solder therein, the upper edge of such pocket or recess being left open by reason of the fact that the raised rib F which extends from the surface of the bond terminal along the lower edge, and at the ends of the terminal portion of the stud, bears against the surface of the rail or other part to be bonded, thereby offsetting the surface of the bond terminal from the rail surface.

In Figs. 4, 5 and 6 we have shown a modified arrangement embraced within the spirit and scope of our invention, wherein the bond terminal G' is provided with a depression H' therein, thereby forming a seat or recess to serve as a receptacle to receive the solder, this depression in the surface of the bond terminal extending from the upper edge of the terminal surface but not entirely to the lower edge thereof, nor to the extreme ends. The surface of the bond terminal which bounds the depressed seat H', when the bond terminal is applied to the rail or other part to be

bonded, bearing against the surface of the rail, enables the solder to be introduced into the pocket or recess H' , which is open at its upper edge, thereby retaining the solder 5 therein and enabling the same to efficiently accomplish the objects and purposes for which said solder is intended.

It is obvious that other modifications and variations would readily suggest themselves 10 to persons skilled in the art and still fall within the spirit and scope of our invention. We do not desire, therefore, to be limited or restricted to the exact details shown and described.

Having now set forth the object and nature of our invention, and various constructions embodying the principles thereof, what we claim as new and useful and of our own invention, and desire to secure by Letters 15 Patent, is:

1. A rail bond having a terminal, said terminal provided with a raised rib extending adjacent the ends thereof and along the lower edge to form a recess or seat which,

when the terminal is applied to the surface 25 of a rail or other part to be bonded, is closed along the lower edge thereof and open along the upper edge thereof to receive solder.

2. A rail bond having a terminal, said terminal provided with a cavity in the inner vertical face thereof, the upper side of said cavity being open for the admission of solder, and the edges of said cavity adjacent the rail being formed in the same plane so as to be parallel with and rest flat against the side of 30 the rail, whereby there is formed between the side of the rail and the terminal a cavity for the reception of a body of solder which may be poured into the cavity through the said opening at the top.

In witness whereof, we have hereunto set our hands this 22d day of November 1904, in the presence of the subscribing witnesses,

GEORGE A. MEAD.

CHARLES R. STURDEVANT
